UNITED STATES PATENT OFFICE.

HUGH DONOHOE, OF NEW YORK, N. Y.

BRAKE FOR DUMB-WAITERS.

SPECIFICATION forming part of Letters Patent No. 404,076, dated May 28, 1889.

Application filed February 15, 1889. Serial No. 300,012. (No model.)

To all whom it may concern:

Be it known that I, HUGH DONOHOE, of the city, county, and State of New York, have invented certain new and useful Improvements 5 in Brakes for Dumb-Waiters, of which the following is a full, clear, and exact description.

The invention relates to brake mechanisms for dumb-waiters; and its object is to furnish a simple and reliable device for conveniently 10 and rapidly braking the main pulley carrying the carriage.

The invention consists of certain parts and details and combinations of the same, as will be fully described hereinafter, and then pointed out in the claims.

Reference is to be had to the accompanying drawings, forming a part of this specification, in which similar letters of reference indicate corresponding parts in all the figures.

20 Figure 1 is a sectional side elevation of the improvement as applied and with parts in section. Fig. 2 is an enlarged plan view of the improvement with the pin in section, and Fig. 3 is a sectional side elevation of the same 25 with parts broken out.

In the dumb-waiter shaft A is held near its upper end the usual frame-work, A', in which is mounted to turn in suitable bearings the shaft B, carrying the carriage-pulley C, over 30 which passes the rope D, supporting the carriage E, mounted to travel vertically in the shaft A on suitable guides and provided with the usual counter-weights to counterbalance the carriage. On the shaft B is also secured 35 a brake-wheel, F, in line with which is held a similarly-shaped wheel, G, secured on a shaft, G', mounted to turn in suitable bearings on the frame-work A'. The shafts B and G' are placed in a horizontal line, as shown, and sufficient space is left between the peripheries 40 of the wheels F and G for the admission of the pin H, provided with a wedge or cone, I, held above the horizontal center of the wheels F and G. The pin H is preferably made of 45 rubber; but other material—such as iron or wood—will also answer the purpose.

From the top of the wedge or cone I extends a pin, H', passing loosely through a suitable guide, H², held in the shaft A. The 50 lower end of the pin H rests in a socket, J', formed on the free end of a brake-shoe, J, fulcrumed at J² to the main frame A'. The

brake-shoe J operates against the periphery of the brake-wheel F. The under side of the free end of the brake-shoe J is engaged by 55 the inner end of the lever K, fulcrumed at K' in the shaft A, and connected at its outer end with a rope, L, extending downward in the front opening of the shaft, as is shown in Fig. 1. The rope L passes in the bottom of the 60 shaft over a pulley, N, and then extends horizontally to pass under a pulley, N', and up over a pulley, N², and then hangs down to support a weight, O, as shown in said Fig. 1. To the outer end of the lever K is also secured one 65 end of a rope, P, which extends upward and passes over a pulley, Q, then extends horizontally and passes over a pulley, Q', from which the rope extends downward and carries a weight, R. The weights R and O counter- 70 balance the lever K and the brake-shoe J, and the rope L serves to move the lever K to any desired position.

The operation is as follows: When the brake-shoe J and the lever K are in the position 75 shown in Fig. 1—that is, the brake-shoe J is disengaged from the brake-wheel F—then the weighted carriage E is locked in place by the wedge or cone I passing against the peripheries of the wheels F and G and preventing a 80 rotary motion of the wheel F. The heavier the weight in the carriage E, the tighter the wedge I will be drawn down between the pulleys F and G. When the operator desires to lower the carriage E with its contents, he 85 pulls slightly on the rope L, so that the lever K, engaging the free end of the brake-shoe J, causes the latter to swing upward, thereby raising the pin H and disengaging the wedge I from contact with the peripheries of the 90 wheels F and G. The wheel F, the shaft B, and the pulley C are now permitted to turn, so that the rope D, with the carriage E, moves downward. The operator usually has hold of the front of the rope D to lower the carriage 95 at any desired rate of speed. The moment he releases his pull on the rope L and lifts the latter to raise the counterbalancing-weight O the brake-shoe J drops downward, so that the pin H slides in the same direction and the wedge 100 I again engages the peripheries of the wheels F and G. The wheel is thus again braked. When the operator hoists the carriage in the usual manner, the pin H is always ready to

drop between the two pulleys F and G whenever the operator releases his hold on the rope, so that the carriage is held in place by pin H engaging the pulleys. The operator can 5 apply the brake-shoe J very suddenly whenever he desires by pulling hard on the rope L, so that the inner end of the lever K throws the brake-shoe J in contact with the periphery of the wheel F. The wedge I is then 10 completely disengaged from the wheels F and G, as is plainly shown in Figs. 2 and 3. Thus it will be seen that by a very simple device I am enabled to brake the main shaft carrying the pulley supporting the carriage whenever 15 desired.

Having thus fully described my invention, I claim as new and desire to secure by Letters Patent—

1. The combination, with two aligning 20 wheels, one of which is secured on a shaft to be controlled, of a brake-shoe held below one of said wheels, and a pin provided with a wedge supported on the free end of the brake-shoe to extend between said wheels, substantially as shown and described.
2. In a dumb-waiter, the combination, with a main shaft supporting the carriage-pulley, of a brake-wheel secured on the said shaft, a second wheel held in line with the said brake-wheel, a pin provided with a wedge and held 25 between the said two pulleys, a brake-shoe adapted to engage the said brake-wheel and supporting the said pin, and a lever operating on the said brake-shoe and under the control of the operator, substantially as shown and described.

adapted to engage the said brake-wheel and supporting the said pin, substantially as shown and described.

3. In a dumb-waiter, the combination, with 35 a main shaft supporting the carriage-pulley, of a brake-wheel secured on the said shaft, a second wheel held in line with the said brake-wheel, a pin provided with a wedge and held between the said two pulleys, a brake-shoe 40 adapted to engage the said brake-wheel and supporting the said pin, and a lever operating on the said brake-shoe and under the control of the operator, substantially as shown and described. 45

4. In a dumb-waiter, the combination, with a main shaft supporting the carriage-pulley, of a brake-wheel secured on the said shaft, a second wheel held in line with the said brake-wheel, a pin provided with a wedge and held 50 between the said two pulleys, a brake-shoe adapted to engage the said brake-wheel and supporting the said pin, a lever operating on the said brake-shoe, and weighted ropes connected with the said lever to counterbalance 55 and operate the same, substantially as shown and described.

HUGH DONOHOE.
